UNITED STATES PATENT OFFICE.

CHARLES PFAU AND EDWARD G. PFAU, OF CINCINNATI, OHIO, ASSIGNORS TO THE PFAU MANUFACTURING COMPANY, OF CINCINNATI, OHIO, A CORPORATION OF OHIO.

ESCAPE-VALVE FOR WATER-CLOSET FLUSHING-TANKS.

No. 883,047. Patented March 24, 1908.

Application filed November 22, 1906. Serial No. 344,565.

To all whom it may concern:

Be it known that we, CHARLES PFAU and EDWARD G. PFAU, citizens of the United States, residing at Cincinnati, in the county 5 of Hamilton and State of Ohio, have invented certain new and useful Improvements in Escape-Valves for Water-Closet Flushing-Tanks, of which the following is a specification.

10 The object of our invention is to provide an escape valve for water closet flushing tanks of simple and economical construction and which causes the maximum drainage or discharge of the tank, and our invention consists in the combination and arrangement of 15 parts hereinafter described and claimed.

In the drawings: Figure 1 is a vertical section of a water closet flushing tank showing an escape valve embodying our invention; 20 Fig. 2, an enlarged section through the valve; Fig. 3, an enlarged section through the ball of the valve; and Fig. 4, a section of a modified form of ball.

The valve seat consists of a cylindrical 25 tube or pipe A adapted to pass through the bottom of tank B and secured in position by a nut C. The bore or discharge opening of pipe A is substantially cylindrical throughout and its upper edges *a* are rounded off just 30 enough to support ball D without cutting it. Ball D is made of rubber or similar flexible material and is of a size to fit well within the mouth of pipe A, the line of contact being well up toward the middle of the ball, as 35 shown. Surrounding the ball at or near its middle is a projecting rib or flange *d* which serves to stiffen the ball against collapsing and also acts as a stop to prevent passage of the ball through the valve seat in case of 40 partial collapse or distortion. To further strengthen the ball we provide a vertical connecting piece *d*¹ which serves to prevent distortions of the ball. At one side the valve seat is provided with a casing E having the 45 port *e* communicating therewith, and carrying the usual overflow pipe F.

Owing to the fact that the ball D has only substantially a line contact with the edges of valve seat A, and that the ball is strengthened and stiffened against collapsing or distorting by rib *d* and connecting piece *d*¹, we are enabled to construct the valve seat to have but a small elevation above the bottom of tank B. Inasmuch as the discharge from 50 tank is limited by the height of the valve

seat above the bottom of the tank, we are thus enabled to obtain the maximum discharge from the tank when the valve is opened.

It is to be understood that in addition to 60 the discharge valve, the tank is to be provided with suitable means of supply and suitable mechanism for operating the valve as will be readily understood by those skilled in the art.

In Fig. 4 we have illustrated a modified construction of the valve ball in which the vertical connecting piece is dispensed with, but the rib *d* is retained to strengthen and stiffen it.

Copending application Serial #334,236 sets forth and claims a float valve comprising a hollow flexible rubber ball with a stay formed integral therein to hold the surface of said ball in its normal shape and that construction is not claimed in this application.

While we have illustrated and described the preferred construction for carrying our invention into effect, this may be varied without departing from the spirit of the invention. We therefore do not wish to be limited to the exact construction set forth but

What we claim as new and desire to secure by Letters Patent is:

1. In an escape valve for water closet flushing tanks, the combination of a flexible valve ball provided with an exterior strengthening rib at or near its middle and an interior vertical connecting piece disposed at right angles to said strengthening rib, with a valve seat consisting of the upper end of an open pipe, substantially as set forth.

2. In an escape valve for water closet flushing tanks, the combination of valve seat A consisting of the upper end of an open pipe of a diameter somewhat smaller than said ball and having rounded edges *a*, with flexible valve ball D having a flexible exterior strengthening rib *d* formed integral therewith and upon the outer surface thereof and in addition thereto to stiffen the ball against collapsing, and adapted to engage said valve seat and serve as a stop in case of partial collapse of the ball, substantially as set forth.

3. In an escape valve for water closet flushing tanks, the combination of a flexible valve ball provided with an exterior strengthening rib at or near its middle and an interior vertical connecting piece disposed at

right angles to said strengthening rib, with a valve seat consisting of the upper end of an open pipe and having substantially a line contact with said ball below the rib, substantially as set forth.

4. In an escape valve for water closet flushing tanks, the combination of valve seat A having rounded edges a with flexible valve ball D having exterior strengthening rib d formed integral therewith and upon the outer surface thereof, and adapted to engage said valve seat and serve as a stop, and interior connecting piece d¹, substantially as set forth.
- 15 5. A valve ball for water closet flushing tanks consisting of a flexible ball D having a flexible exterior strengthening rib d near its middle formed integral therewith upon

the outer surface thereof to stiffen the ball against collapsing, and adapted to engage 20 said valve seat and serve as a stop in case of partial collapse of the ball, substantially as set forth and for the purposes specified.

6. A valve ball for water closet flushing tanks consisting of a flexible ball D having 25 an exterior strengthening rib d at or near its middle formed integral therewith and upon the outer surface thereof, and adapted to engage a valve seat and serve as a stop, and an interior connecting piece d¹, substantially as 30 set forth and for the purposes specified.

CHARLES PFAU.
EDWARD G. PFAU.
